UNITED STATES PATENT OFFICE

2,064,649

ELASTIC FLUID TURBINE

John H. Doran, Scotia, N. Y., assignor to General Electric Company, a corporation of New York

Application February 12, 1935, Serial No. 6,198

6 Claims. (Cl. 60—95)

The present invention relates to elastic fluid turbines for driving propellers or generators, more particularly to the support and the arrangement of the exhaust casing of turbines used for propelling ships. As is well known, elastic fluid turbines expand and contract due to heating and cooling during operation, which makes it necessary to provide supporting means permitting expansion and contraction of the turbine casing to avoid the setting up of undesirable stresses.

One object of my invention is to provide an improved construction and arrangement of turbines whereby they may expand and contract in axial direction due to heating and cooling during operation without causing high bending and other stresses being set up in the turbine and the elements connected thereto.

I have found that the supports for a turbine should be provided as near as possible to the center line of the turbine wherever such turbine drives a propeller through the intermediary of a gearing. As the available space in many cases, especially where such turbines are arranged on boats, is very limited the head room required for the turbine should be kept a minimum. This is accomplished in my invention by the provision of a turbine casing arranged to form its own supporting structure. To this end, the side walls of the lower half of the exhaust casing of such turbine are extended at each end far enough to be clear of the condenser underneath. This permits the provision of supports for the casing end extensions or projections without interfering with the condenser arrangement. The condenser is preferably directly supported by the exhaust casing.

For a better understanding of what I believe to be novel and my invention, attention is directed to the following description and the claims appended thereto in connection with the accompanying drawing which forms a part of my specification.

In the drawing, Fig. 1 illustrates a front view of a turbine arrangement embodying my invention, Fig. 2 is an enlarged perspective view of a part of Fig. 1 and Fig. 3 is a perspective view of a part of the turbine casing in Fig. 1.

The arrangement comprises an elastic fluid turbine having a shaft 1 connected to a gearing 2 for driving a propeller shaft 3. The turbine shown is of the double flow type having an inlet 4 connected to a welded hood 5, which latter is flanged to a welded exhaust casing or hood 6. The exhaust casing 6 (Fig. 3) com-

prises two co-axially extending side walls 7 and 8 respectively and transverse extending front and rear walls 9 and 10 respectively united with the side walls by welding to form a box-like structure. Transverse partitions 11 and 12 are united with the side walls together with cover plates 13 and 14 have recesses 15 to accommodate bearings for the turbine shaft 1. A condenser 17 for condensing exhaust elastic fluid of the turbine is connected to and supported by the exhaust casing 6. Both the gearing and the turbine are supported on a floor 18 which may be a part of the bottom structure of a ship. The gearing 2 is rigidly supported on a framework 19 secured to the bottom 18. According to my invention I provide the lower casing half or exhaust hood 6 with axial extensions or projections 20 and 21 projecting axially beyond the condenser 17. The front projection 20 is rigidly supported on a structure 22 resting on the bottom 18, whereas the rear casing projection 21, according to my invention is indirectly and yieldably supported on the bottom 18. More specifically, the support for the rear projection 21 comprises walls, pillars or posts 23 resting on the bottom 18. Cross-beams, in the present instance shown as two channel or U-irons 24 and 25, having their bottom portions adjacent each other and spaced apart are supported on the posts 23. The channel irons 24 and 25 in turn support two angle irons 26 and 27 having adjacent portions engaging a plate 28. An upper portion of the plate 28 is fastened to the angle irons by means of bolts 29. An end plate 30 for reinforcing the end wall 10 of the projection 21 is fastened to a lower portion of the plate 28 by means of bolts 31. Thus, the plate 28 running transverse to the turbine shaft has a lower portion fastened to the exhaust casing and an upper portion fastened to the supporting structure. The supporting structure together with the plate 28 which is flexible in axial direction of the turbine, forms in substance a means for yieldably supporting the turbine to permit axial expansion and contraction of the turbine. Transverse movement of the yieldably supported turbine part, owing, for instance, to rolling of a boat, is substantially prevented due to the stiffness of the plate 28 in transverse direction.

During operation of the turbine the casing expands in the direction of the rear projection 21 because the front projection 20 is rigidly supported. The flexibility of the supporting structure, in particular the plate 28, in axial direction of the turbine prevents the setting up 55

of stresses in the turbine or in the support by the expansion and contraction of the turbine casing.

From another viewpoint, my invention comprises two supporting beams 7 and 8 extending in axial direction of the turbine with their upper ends at a level near the horizontal plane through the turbine shaft. These two co-axially extending beams 7 and 8 are united by end walls and partitions 9, 10 and 11, 12 respectively defining a portion of the exhaust casing and projections 20 and 21. The turbine exhausts into the box-like structure defined by the walls 7, 8, 11 and 12. The walls are arranged to directly support the condenser 17. The projections 20 and 21 extending axially beyond the condenser 17 are supported by a rigid support 22 and a flexible support 28 respectively, preventing relative movement of one turbine end and permitting such 20 relative movement of the other turbine end.

What I claim as new and desire to secure by Letters Patent of the United States is:

1. The combination of a turbine having a box-shaped welded exhaust casing with axial extensions, means for yieldably supporting the axial extensions to permit expansion and contraction of the casing comprising a plate running cross-wise to the turbine shaft and having a portion fastened to one of the extensions, and means for rigidly supporting another portion of the plate, said exhaust casing forming a support for the entire turbine and a condenser fastened to the exhaust casing.

2. In a ship's drive, an elastic fluid turbine having a box-shaped welded exhaust casing with axial extensions, a gearing and a propeller shaft driven from the turbine, means for rigidly supporting the extension of the turbine exhaust casing facing the gearing, and means for yieldably supporting the extension facing away from the gearing.

3. In a ship's drive, an elastic fluid turbine, a gearing and a propeller shaft driven from the turbine, a condenser connected to and supported by the turbine casing, means for rigidly supporting a portion of the turbine casing facing the gearing, and means for yieldably supporting

a casing portion facing away from the gearing, said last named means comprising two channel irons having bottom portions facing each other and being spaced apart, angle irons resting on top of the channel irons and a plate having an upper portion held between the angle irons and a lower portion fastened to said portion of the turbine casing facing away from the gearing.

4. The combination of a turbine with a welded casing comprising a hood and an exhaust casing fastened together, the exhaust casing including side walls coaxial with the shaft and of a height extending substantially to the level of the turbine center line, and front and rear walls extending transverse to the shaft and being welded to the side walls to form a box-like structure, a condenser fastened to and supported by a lower portion of said structure, the front and rear portions of the structure extending axially beyond the condenser, means fastened to the front wall for rigidly supporting the extending front portion, and means fastened to the rear wall for yieldably supporting the rear extending portion to permit expansion and contraction of the casing without setting up undesirable stresses therein.

5. In a double flow turbine, an exhaust casing comprising two coaxially extending side walls, transverse extending front and rear walls welded to the side walls, and partitions defining bearing supports being welded to the side walls, a condenser fastened to the exhaust casing, the casing projecting axially beyond the condenser to permit supporting of the projecting portion without interfering with the condenser arrangement.

6. In a turbine installation, a turbine, two supporting beams extending parallel to the turbine shaft and being of a height extending substantially to the level of the turbine center line, walls uniting the supporting beams to define at least a part of the turbine exhaust casing, and a condenser fastened to the beams for receiving exhaust fluid from the exhaust casing, said beams extending axially beyond the condenser.

JOHN H. DORAN.
